UNITED STATES PATENT OFFICE

CALEB E. SUMMERS, OF DETROIT, MICHIGAN, ASSIGNOR TO GENERAL MOTORS RESEARCH CORPORATION, OF DETROIT, MICHIGAN, A CORPORATION OF DELAWARE

FUEL SYSTEM

Application filed June 5, 1926. Serial No. 113,933.

This invention relates to improvements in the fuel system for explosive motors. The invention is primarily intended for use on motor vehicles although its advantages, when 5 so used, may also be present, perhaps to a less extent, in other relations. Furthermore, while designed for use on an engine of the four cycle type its characteristics are such as to render it useful also on engines of the 10 two cycle type.

It is, then, the object of the invention to provide a fuel system having parts co-related to obtain maximum efficiency; one which will use advantageously explosive fuel difficult of 15 vaporization; one which is adapted for all conditions of speed, load, temperature and pressure.

The duty of a fuel system is to bring fuel from a storage tank at the rear; meter it correctly for every condition of speed, load, and temperature; and introduce it in an atomized state so it is carried directly, borne by the air charge, into each separate cylinder. The fuel should be automatically regulated for 25 every requirement, as, extra rich for cold starting, full power mixture for full load, and maximum economy mixture for part load. The fuel system should also be so designed as to get the maximum air charge into the 30 motor at full load. To accomplish this, pre-heating must be eliminated, and also any resistance to the entrance of the air, such as valves, is undesirable. It is desirable even to go further, and so construct the manifold 35 that an air ram condition is produced, which actually supercharges the engine, obtaining more power from a given bore and stroke, yet without increasing the speed or compression (which latter two carry with them certain 40 disadvantages). This results in a lighter motor for equal power, which not only saves cost of material, but saves weight, which again results in better performance for the same power. Also a smaller engine with less 45 cooling surface, of less mechanical friction, results in greater economy. It is, therefore, a fundamental gain to obtain as great a weight of charge as possible in a given cylinder.

50 For the attainment of the objects enumer-

ated, the structure herein described and illustrated in the accompanying drawing has been devised.

In the drawing:

Figure 1 shows an internal combustion 55 engine in end elevation, partly in section.

Figure 2 is a side elevation with the fuel system in vertical section.

Figure 3 is a horizontal section on line 3—3 of Figure 2.

Figure 4 is a horizontal section on line 4—4 of Figure 2.

Figure 5 is a vertical section of a detail.

Referring by reference characters to the drawing, numeral 1 shows an internal combustion engine having exhaust manifold 2. The cylinders 3 are surrounded by a water jacket 4. Over the cylinder block is a co-operating head 5 which may be shaped as shown, and in which head are mounted the 50 spark plugs 6. Associated with each cylinder is an intake valve 7 affording communication with the combustion chamber 8 and the manifold 9. At this point there is a departure from the conventional arrangement. 75 There are a plurality of tubular manifold members which are secured to openings 9' in the cylinder block and extend downwardly and are united by a common casting 10 controlled by the usual throttle valve 11. By 80 this type of manifold construction each cylinder draws in its air through a tube which is not being used at the time by any other cylinder, that is, there is no overlapping of induction flow to two cylinders through the 85 same tube. By proper selection of length and diameter of the tube, the ram effect will be varied along the speed range so as to obtain the maximum ram at the speed desired. For instance, if high torque at high speed is 90 the principal requirement, the ram will be relatively short and large in diameter; if high torque at low speed is more important, the ram will be relatively long and of small 95 diameter. In practice, for application to an Oakland engine, the ram tubes will be approximately $\frac{7}{8}$ " inside diameter and 19" long. In the construction of a ram, it is desirable to have the inner surface smooth and all bends over as long radius as possible. 100

Where there is a change in section, as where the ram enters the port, the increase in diameter should be gradual so there is no distant ledge which will cause eddy currents of the air and dissipate energy in fluid friction.

5 Air pumps 12, of which there may be two, are driven from the motor as by a shaft 13, gearing '13', shaft 14, universal 15, crank shaft 16, connecting rods 17 and piston 18. 10 The air pumps draw air by means of an inlet valve 19 through which air enters from a tube 21. Tube 21 takes its air from any convenient source but preferably from the crank case since in that way the air would be free 15 from dirt and contain a desired quantity of oil mist. A resistance valve, not shown, is used in pipe 21 to maintain a definite vacuum. This vacuum is communicated by pipe 23 to float chamber 24 having a float 25 controlling 20 a valve 26. Obviously the degree of vacuum must be sufficient to lift the fuel from the storage tank to the float chamber under the most adverse conditions and maximum demand, that is, it must lift sufficient fuel for 25 maximum engine speed at full load when climbing the steepest grade so the car will pull on low gear and with the storage tank practically empty.

The air inlet valve 19 is mechanically operated and driven by shaft 27 geared by gears 28 and 56 to the crank shaft. The fuel for the float chamber is obtained by a pipe 29 extending from the usual gas reservoir at the rear of the car and enters a chamber 30 beneath the float chamber. Here it is filtered by filter 32 and passes through the valve 26 into the float chamber.

To meter the fuel one or more rotating cylinders 33 are used. The two cylinders 40 shown are mounted so as to be capable of simultaneous vertical reciprocation and each is mounted for rotation on its own longitudinal axis. Each cylinder rotates in a chamber filled with fuel entering from the float 45 chamber through passage 34 (see Figure 3). Shoes 35 actuated by a spring 36 mounted on a post 37 hold about 90° of the circumference of the cylinders 33 against the encircling walls of the fuel chamber. The cylinder 50 walls are provided with pockets 38 of variable depths, being deepest at their lowermost portion. These pockets become filled with fuel during the rotation of the cylinder within the fuel chamber. The pockets 38 55 come into registration with the openings 39 in the fuel chamber as the cylinder rotates on its axis and the openings 39 communicate by means of pipes 40 with each of the valve chambers, as clearly shown in Figure 1. The 60 pipes 40 terminate in nozzles 41 situated just beneath the intake valves. The fuel pockets 38, when rotated into registry with opening 39 also register with elongated openings 44 in the walls of the fuel chamber, said elongated openings 44' communicating with a

vertical passage 44 receiving air under pressure from the air line 42 through openings 43, this air line receiving air under pressure from pump cylinders 12. Thus, when pocket 38 registers as stated and as shown compressed air from pump 12 sweeps the fuel from the pocket and carries it through the tubes 40 and to the nozzle at the open intake valve.

70 The position of the metering cylinder and fuel pocket shown is for maximum fuel requirement, that is, for full load when the motor is at its lowest temperature. For operation under normal conditions of temperature and for part load, the metering cylinder is moved downward so the fuel in the lower portion of the fuel pocket does not discharge through the port, but is carried past it. The means for moving the metering cylinder as actuated by temperature and load are as follows:

75 The shaft 45, which drives the metering cylinders, extends downwardly as at 46. This shaft and its companion shaft 47, which drives the other metering cylinder, are driven by gears 53 on the shafts. Gears 53 engage 80 gear 55, which is integral with the gear 57, rotated by the gear 56 on the crank shaft as shown in Figure 1 and Figure 3. The shafts are coupled by a yoke 48 which permits them to rotate independently but causes 85 them to move together in any vertical movement. The yoke 48 has a pivot shaft 49 upon which is a lever 50, one end of which is connected to a piston 51 of a cylinder 52.

90 Cylinder 52 is connected by a conduit 58 entering the manifold at 59 just above the throttle 11. A spring 60 within cylinder 52 exerts its pressure upwardly upon piston 51. It is evident that when the vacuum in the manifold increases, due to the closing of the 95 throttle, the piston 51 will be drawn downwardly carrying lever 50, yoke 48 and the metering cylinders. By the selection of a spring of suitable tension and by properly shaping the pockets 38, it is possible to make 100 the quantity of fuel discharged by the metering cylinders correspond to any degree of throttling, since the fuel content is reduced 105 in proportion to the absolute pressure of air in the manifold, it being understood that the 110 fuel in the fuel pocket 38 beneath the discharge opening 39 is not driven out through the conduit 40.

115 Air expands with increase in temperature. Therefore, a cylinder full of air at minus 20° F. will require more fuel than the same volume at 200° F. Provision is made, therefore, to regulate the fuel in proportion to temperature. A bellows 61 is provided separated by 120 partition 62 from an inclosure 63. The inclosure 63 is in communication by means of a tube 64 with a chamber 65 located within the water jacket of the motor so that the water temperature is imparted to it. The bellows 61 is entirely filled with oil or other 125

non-volatile liquid and it communicates by means of a small hole 61' through partition 62 with enclosure 63, the lower-most part of the enclosure also containing oil.

5 The size of the enclosure is so selected that when the bellows is fully extended downward, liquid from the enclosure may flow through a small hole in the partition entirely filling the bellows, with a certain reserve left in the enclosure. Also when the bellows is at its upward limit, thereby forcing the liquid out through the aperture in the partition into the enclosure, the enclosure will not be entirely filled. The purpose of the liquid 10 is to give stability to the bellows so that when sudden shocks are imparted to the bellows through the sudden and forceful change in the vacuum that controls the piston 51, the shock imparted to the bellows through the 15 lever and the connection will not cause it to move suddenly, because a considerable time element will be required for the oil to be forced through the aperture in the partition. However, on the other hand, when the temperature of the water jacket changes and 20 causes an expansion of the air in the chamber, the persistent pressure exerted on the surface of the liquid in the enclosure will cause the liquid to flow through the aperture, thus extending the bellows; and conversely when a contraction of the air in the chamber produces a partial vacuum, the air pressure exerted on the external walls of the bellows will force the bellows upward, depressing the portion of the liquid contained 25 therein into the enclosure. Therefore, by this arrangement we have a mechanism which is resistant to sudden shocks, but regulates with accuracy to compensate for changes in 30 the temperature of the motor. The chamber may be placed at any position to have the temperature of any portion desired imparted to it, but it is thought the water represents a fair index of the temperature of the working fluid in the cylinder during the intake 35 stroke. The bellows 61 is secured to the casting 67 by its upper end so that its expansion has the effect of pulling down on leaf spring 68 imparting downward motion to the yoke 40 45 and the metering cylinders.

The bellows has been described as correcting for variations in temperature, but it is evident that it will also correct for changes in barometer or altitude. Suppose a motor 50 so equipped is placed in an airplane and is operated from the ground to a high altitude; the bulb, the tube, the chamber, and the bellows are sealed under stated conditions of air temperature and pressure. As the airplane reaches higher altitudes where the air pressure is less, the external pressure, which held the bellows in its position at the ground, is reduced so the pressure of the air in the bulb tends to expand and force the bellows 55 down against the reduced air pressure. This

results in reducing the quantity of fuel which is being fed to the motor so a balanced mixture is maintained.

We have, therefore, combined in one unit means for elevating the fuel from the storage 70 tank, metering the fuel to the requirements of the engine, the metering being regulated automatically for all changes of load, speed, temperature, and barometer. The fuel is introduced at each valve pocket in the form of 75 a spray, produced by compressed air, so the distribution should be perfect and the introduction positive and almost instantaneous. The ram manifold, which is possible with this type of metering, increases the air charge 80 very appreciably through the ordinary driving range.

From the combination of ram manifold, cold carburetion and perfect distribution, the power of the engine may be increased by approximately 20%. The method of fuel introduction is intended to insure easy starting at any temperature. It is expected that an engine equipped as described will start and operate satisfactory on half kerosene and 85 half gasoline, even in winter. Fuel economy will be uniformly high whether the car is driven by an expert or an amateur, since all regulation is automatic.

I claim:—

95

1. In combination with an internal combustion engine, a mechanical metering device therefor comprising a fuel conduit communicating with said engine, a fuel chamber, a metering member rotatable and reciprocable 100 therein, said metering member having a pocket to receive fuel from said chamber and deliver it to said conduit, means automatically controlled to reciprocate said metering means and thereby predetermine the amount of fuel 105 discharged from said pocket to said conduit.

2. Mechanical metering mechanism for an internal combustion engine having a cylinder and an intake manifold comprising a fuel chamber, a plurality of metering members 110 therein, power driven means to rotate said members, delivery conduits from said chamber to said cylinder for supplying the engine with fuel, said metering members having pockets to be filled with fuel from said chamber and to discharge into said conduits, pressure means to force said fuel through said conduits, and mechanism automatically actuated by variations in manifold suction, 115 engine temperature and external pressure to reciprocate said metering members jointly to thereby vary the area of said pockets in registering with said conduits.

3. The combination of elements enumerated in claim 2, said mechanism comprising rod means on each metering member, a device responsive to changes in manifold suction operative upon one arm of said lever and a device responsive to changes in temperature 125 130

and pressure operable upon the other arm of said lever device, the other arm being actuated by said temperature control.

4. The combination of elements enumerated in claim 2, said mechanism comprising a head connected to said metering members, a fixed cylinder, a piston therein connected to said head, a pipe connecting said cylinder with the manifold and yielding means within said cylinder whereby the suction of the manifold and the yielding means cooperate to reciprocate said metering device to vary the quantity of fuel delivery.

5. The combination of elements enumerated in claim 2, said mechanism comprising a head connected to said metering members, an expansible and contractible member being connected to said head, whereby changes in motor temperature control the quantity of fuel supplied by said metering device.

6. In combination, an internal combustion engine, a float chamber for fuel, a mechanically motor operated air pump, pipe means between said air pump and said fuel chamber whereby the fuel chamber is supplied with fuel by the suction stroke of the pump, other pipe means associated with said air pump and fuel chamber and engine whereby fuel is delivered from said chamber to said engine by air pressure caused by the discharge stroke of said pump.

7. In an internal combustion engine having a cylinder and intake manifold, a fuel chamber, a first conduit from said chamber to said cylinder, a second conduit to supply said chamber with fuel from a source below said chamber, an engine operated air pump, an inlet pipe therefor, a pipe from said inlet pipe to said fuel chamber, mechanism including a third conduit between said pump and the first conduit, whereby the suction stroke of said pump operates to maintain a supply of fuel in said chamber through the second conduit and whereby the discharge stroke of said pump operates to deliver a supply of fuel under air pressure from said chamber to said cylinder through said first conduit.

8. The invention defined by claim 7 together with an engine operated metering device in said chamber to predetermine the quantity of fuel to be delivered.

9. The invention defined by claim 7, together with an engine-operated metering device in said chamber to predetermine the quantity of fuel to be delivered, and mechanism responsive to changes in manifold suction and also to variations in temperature and pressure to control the metering device.

In testimony whereof I affix my signature.
60 CALEB E. SUMMERS.
